United States Patent Office

Des. 214,655
Patented July 8, 1969

214,655

VERTICAL BARBEQUE UNIT

Thomas Wayne Miles, Los Angeles, Calif.
(6331 Hollywood Blvd., Hollywood, Calif. 90028)

Filed July 23, 1968, Ser. No. 12,855

Term of patent 14 years

Int. Cl. D7—04

U.S. Cl. D81—10

FIG. 4.

FIG. 5.

FIG. 6.

FIG. 1 is a front isometric view of a vertical barbecue unit embodying my new design, with numbered arrows designating the directions of the succeeding views;

FIG. 2 is an end view of the same;

FIG. 3 is a rear elevational view of the same;

FIG. 4 is a top plan view of the same;

FIG. 5 is a front elevational view of the same;

FIG. 6 is an end view taken from the end opposite from FIG. 2.

I claim:

The ornamental design for a vertical barbecue unit, substantially as shown.
